To all whom it may concern:

Be it known that I, Edwin H. Davis, a citizen of the United States, residing in the city and county of San Francisco, State of California, have invented a certain new, original, and ornamental Design for a Liquid Measuring and Pouring Attachment for Bottles, of which the following is a specification, reference being had to the accompanying drawing, forming part thereof.

Figure 1 is a side elevational view of a liquid

measuring and pouring attachment for bottles, showing my new design.

Figure 2 is a front elevation.

Figure 3 is a rear elevation.

Figure 4 is a top plan view.

I claim:

The ornamental design for a liquid measuring and pouring attachment for bottles, as shown.

EDWIN H. DAVIS.
